Connected Bike Training Bike 900 by Domyos dated Jan. 24, 2025. Found online [Apr. 24, 2025] https://www.decathlon.co.uk/p/connected-bike-training-bike-900/_R-p-347445?mc=8806819 (Year: 2025).*

Primary Examiner — Ryan Harvey(74) *Attorney, Agent, or Firm* — Nikitas E. Nicolakis; Lombard & Geliebter LLP(57) **CLAIM**

The ornamental design for a training bicycle as shown and described.

DESCRIPTION

FIG. 1 is a perspective view of the training bicycle showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.
